UNITED STATES PATENT OFFICE.

SEMAN A. SWENARTON, OF MONTCLAIR, NEW JERSEY, AND HENRY M. KEISER, OF BROOKLYN, NEW YORK.

DESIGN FOR ORNAMENTATION OF Undershirts.

SPECIFICATION forming part of Design No. 14,985, dated April 29, 1884.

Application filed January 28, 1884. Term of patent 14 years.

To all whom it may concern:

Be it known that we, SEMAN A. SWENARTON, a citizen of the United States, residing at Montclair, in the county of Essex and State 5 of New Jersey, and HENRY M. KEISER, a citizen of the United States, residing at Brooklyn, in the county of Kings and State of New York, have invented and produced a new and original Design for Ornamenting the Pocket-10 Slits in Ladies' Knit Undershirts, of which the following is a specification.

Reference is to be had to the accompanying drawing, forming a part of this specification, in which a face view of a lady's knit under-15 shirt or vest having the edges of the pockets ornamented according to our new design is shown.

The knit undershirt A is provided with breast-pockets C.

Heretofore the edges of the pocket-slits have 20 been finished with a tape binding. In our new design the edges of the pocket-slits B are embroidered.

In the drawing two kinds of embroidery are shown.

We claim—

The herein-described design for ladies' undershirts, consisting of a shirt having embroidered breast-pocket slits B, as shown.

SEMAN A. SWENARTON.
HENRY M. KEISER.
